WATCHCASE

James E. Thurmond, Atascadero, Calif.

Application October 25, 1930. Serial No. 491,275

1 Claim. (Cl. 58—90)

This invention relates to watch cases, and more particularly to an improved waterproof and dust proof construction.

Numerous ways of constructing a watch case so as to render the same waterproof and dust proof have been proposed, but most of these constructions, for various reasons, have been very unsatisfactory, as for example, because of the difficulties connected with their manufacture, 10 and the like, making the cost of such a watch very high. Also, one of the main objections to the known types of constructions is the loss of the water and dust proof feature once the watch case is opened, either because of carelessness in 15 closing or reassembling, or because of the inability to return the various parts to their original positions.

It is an object of the present invention to provide a watch case which will retain its waterproof characteristic indefinitely.

A still further object of the invention is to provide a waterproof watch case construction which permits of setting of the watch while exposed to moisture, dust, and the like, yet excluding the entrance of these elements thereto.

Another object of the invention is to provide a novel means for securing the back to the watch case, the usual screw threads or hinges being eliminated, such a construction being especially 30 adapted to the provision of a ready and simple means for effecting a water and dust proof sealing.

Other and further objects and advantages of the invention will be hereinafter set forth and 35 the novel features thereof defined by the appended claim.

In the drawing:

Fig. 1 is a front elevation of a wrist watch, the case of which is constructed in accordance with 40 my invention;

Fig. 2 is a rear elevation of the case shown in Fig. 1, portions thereof being broken away, and the dotted lines indicating the position of the back for removal or application thereto;

Fig. 3 is an enlarged fragmentary detail sectional view of the pendant assembly, the dotted lines indicating the position of the crown for setting the hands;

Fig. 4 is an enlarged detail sectional view taken 45 on the line 4—4 of Fig. 3;

Fig. 5 is a view in elevation of the inner side of the back; and

Fig. 6 is an enlarged fragmentary detail sectional view taken on the line 6—6 of Fig. 2.

50 Like reference characters designate corre-

sponding parts in the several figures of the drawing wherein 1 denotes generally a wrist watch having the usual strap or bracelet 2 secured thereto at opposite sides of the same, and a crown 3 to be hereinafter more fully described. The strap or bracelet is preferably secured to the watch case by means of the strap lugs 4 having a removable connecting bar or pin 5 extending therebetween through suitable looped ends 6 or catches on the strap or bracelet. The bars 5 are preferably removable and provided with a screwdriver engaging head 7 adapted to be recessed in one of the lugs 4, the opposite end of the bar being threaded into the corresponding lug.

By undercutting the lugs 4, as at 8, to form grooves substantially in the plane of the rear of the watch case, and providing the back or cover 9 with correspondingly spaced projections 10, a simple and excellent means for securing the back to the case is provided. The back is also preferably provided on its inner side with spaced annular flanges 11 and 12 adjacent to the edge thereof, forming a recess therebetween into which a suitable sealing or packing member 13 is placed. The packing member, which is in the form of a gasket ring, may be made from rubber composition or like material of a resilient and waterproof nature. If desired, the packing may be saturated with oil or other waterproof substance, but this is not absolutely necessary if the proper material is used.

The watch case is also provided with an annular flange 14 so as to be located intermediate the flanges on the back to engage the packing when the back is secured to the case, the inner flange 12 of the back being adapted to engage the works 15 to hold the same against the bezel 16.

Formed on the back intermediate one of the pairs of projections 10 which cooperate with the strap lugs 4 is a pry engaging member 17 having a notch 18 formed therein into which a screwdriver or the like may be inserted. The projection 17 is preferably positioned so as to be in close proximity to one of the lugs 4 when the back is in secured position. By inserting the screwdriver in the notch and prying against the adjacent lug 4, as a fulcrum, the back may be rotatably shifted for disengaging the projections 10 from the grooves in the lugs, as indicated by the dotted lines in Fig. 2, to permit removal of the back. Obviously, to replace the back in secured position, the projection 17 is suitably forced in the opposite direction to cause the

projections 10 to enter the grooves in the lugs 4, thereby effectively sealing the back with respect to the case. When the bar 5 is in position connecting the strap lugs between which the 5 projection 17 extends, the bar acts as a guard to prevent accidental displacement of the back.

Referring now to the pendant assembly, 19 denotes a pendant having an inwardly turned flange 20 formed on the outward end thereof, 10 the crown 3 being provided with a central tubular shank or sleeve 21 extending into the pendant and having threaded engagement with the watch stem 22. A jam or lock screw 23 suitably fastens the crown to the stem. The stem 15 is preferably provided with an abutment flange 24 located adjacent the inward end of the pendant, a spring 25 encircling the tubular shank 21 and having its opposite ends engaging the flanges 20 and 24 to normally maintain the stem 20 in an inward position. To set the hands, the crown is pulled outwardly against the action of the spring, as indicated by the dotted lines in Fig. 3. Such construction positively prevents the loss of the stem from the watch, as frequently occurs in the usual constructions now 25 on the market.

Intermediate the sides 26 of the crown and the pendant 19, is a tubular packing or sealing member 27 formed of material similar to the 30 packing 14 in the back. When the crown is in its normal inward position, the packing 27 is firmly compressed between the sides of the crown and the pendant, as well as between the case of the watch and the top of the pendant, 35 the spring 25 aiding in such compression. Such a construction permits setting of the watch without breaking the seal, except as to one point which is between the packing and the watch case, thereby excluding the entrance of dust 40 and moisture even during the setting operation, by virtue of the seals maintained at the other points.

The operation of the crown and back should be obvious from the foregoing. It is to be understood that the sealing of the back with re-

spect to the case may be accomplished in just the reverse manner as hereinbefore described, the annular flanges forming the recess for the packing being formed on the case instead of on the back and the packing carried therebetween by the case. In this construction, the back would carry the annular flange which falls intermediate the flanges on the case to engage the packing.

By providing the back with a pry engaging member, a more effective seal can be produced between the back and the case, as distinguished from the usual seals employed with backs having screw threaded or hinged engagement with the case, the screw threaded constructions being entirely dependent upon friction with the hand to screw the same tightly into sealed position. A considerable leverage may be obtained in applicant's construction, thereby positively insuring a water and dust proof seal.

While the specific details of construction have been herein shown and described, the invention is not confined thereto as changes and alterations may be made without departing from the spirit thereof as defined by the appended claim.

Having thus described my invention, what I claim as new and desire to secure by Letters Patent is:

A pendant assembly for watch cases of the class described, comprising a pendant having an inwardly flanged outer end, a crown adapted to fit over said pendant, said crown having a central tubular shank extending into said pendant, a stem in said pendant projecting into said shank in threaded engagement therewith, said stem having an abutment flange formed thereon adjacent to the inward end of said pendant, a jam screw for locking said crown with said stem, a spring encircling said shank and engaged at its opposite ends by the flanges on said pendant and stem, and a sealing member intermediate said crown and pendant.

JAMES E. THURMOND.
